TRAIN-PIPE VALVE.

1,275,243.

Specification of Letters Patent.

Patented Aug. 13, 1918.

Application filed December 21, 1917. Serial No. 208,316.

To all whom it may concern:

Be it known that I, EDWARD E. GOLD, a citizen of the United States of America, residing in the borough of Manhattan, city, county, and State of New York, have invented certain new and useful Improvements in Train-Pipe Valves, of which the following is a specification.

This invention relates to an end valve for 10 train-pipes in railway car heating systems, the purpose of such valves being to close off the train-pipe at the rear of the last car of the train.

My invention relates to train-pipe valves 15 of the type comprising a shell or valve casting adapted for connection to the train-pipe and having an internal seat and a plunger movable in the shell to close against such seat in one position, or in its opposite position to be withdrawn therefrom to leave a clear way through the valve. When such valves are used as end train-pipe valves the seat communicates with an outlet passage 20 adapted for connection to the nipple carrying the steam coupled hose. Such end valves are sometimes provided with a restricted drip outlet or bleeder port for blowing off steam and condensation from the rear of the train-pipe, such orifice being closed when 25 the main valve is open, and vice versa.

Train-pipe valves of the character described are set forth in the following prior 30 patents granted to me, upon which the present invention constitutes a further improvement:

No. 498,545, of May 3, 1893;
No. 585,383, of June 29, 1897;
No. 756,492, of April 5, 1904;
No. 806,970, of December 12, 1905.

Such train-pipe valves have been sometimes applied at the middle of the car where the branch pipes lead from the train-pipe to enter the car; and in other cases have been applied at the ends of the train-pipe 45 where it connects with the hose.

The present invention is designed to improve the construction of the train-pipe valve to facilitate getting access to the internal plunger and its removal for repacking, and to provide a convenient construction of adjustable drip outlet or bleeder. Formerly it was necessary, in order to remove the plunger, to take off a cap closing the top of the valve shell, and after lifting 50 out the plunger-operating stem to then lift

the plunger out through the top opening; or else to disconnect the pipe or hose connection, or, in other words, to remove the train-pipe valve from its connection with the pipe or fittings on one or both ends and then withdraw the plunger through the end opening thus provided. According to the present invention the plunger, instead of moving in line with the steam pipe, moves in a plunger chamber which is out of line 60 therewith and preferably transverse thereto, and the shell has an opening in line with the plunger sufficiently large to withdraw the plunger endwise through such opening, a cap being provided for closing the opening 65 when the plunger is in place. This cap is utilized to form a seat against which the plunger seats when the valve is wide open, whereby to shut off communication between the interior of the shell and a drip outlet 70 or bleeder orifice which is most conveniently applied to such cap. For adjusting the outflow through this bleeder orifice in the valve at the end of the train, an adjusting screw forming a needle valve is provided. The 75 valve shell is formed with an outlet beyond its normal seat which is curved laterally or downwardly and terminates preferably in an oblique connection for the direct attachment thereto of the hose nipple, thus avoiding the necessity of interposing a skewed outlet elbow such as has heretofore been 80 commonly used.

The preferred embodiment of the invention is shown in the accompanying drawings, in which—

Figure 1 is a vertical section in a plane transverse to the car and looking from the end of the car toward the middle thereof, the section being in the plane of the line 95 1—1 in Fig. 3.

Fig. 2 is a vertical section in a plane parallel with and nearly coincident with the axis of the train-pipe, as indicated by line 2—2 in Fig. 3;

Fig. 3 is a horizontal section in the planes of the lines 3—3 in Figs. 1 and 2;

Fig. 4 is a plan showing the valve shell and train-pipe and hose connections on a reduced scale, the cap and plunger being 105 removed.

The end valve is shown closed in Figs. 1 and 2, and open in Fig. 3.

In the drawings, A is a portion of the train-pipe extending longitudinally of a car. 110

B is, as a whole, the end train-pipe valve, and C is the hose. The valve B comprises a shell or casing D having a cap E, and an inclosed plunger F movable in such shell and 5 an operating stem G for actuating the plunger. The shell D comprises a neck *a* and a boss *b* forming a train-pipe connection, the train-pipe being screwed or otherwise joined to such boss; a plunger chamber *c* in which 10 the plunger F may move; an outlet passage *d* terminating in a boss *f* for connection with the hose nipple; and a valve seat *g* intervening between *c* and *d* so that when the plunger is closed against this seat the 15 valve is shut. The cap E closes an opening *h* in the end of the plunger chamber opposite to that occupied by the seat *g*; this opening being large enough to permit the plunger to pass freely out through it. The cap 20 preferably screws into this opening, as shown. The cap is formed with a seat *i* against which the plunger closes when the valve is open (see Fig. 3). When the valve is shut (Fig. 1) there is free communication 25 between the neck *a* and the space within the seat *i*, from which space leads the drip outlet or bleeder duct *j*, which is shown as formed by drilling holes at right angles in the cap. One of these holes is counterbored 30 and threaded to receive an adjusting screw *k*, the inner end of which enters into the drip orifice and may more or less close it in order to adjust the area of this orifice and regulate the rate at which steam and 35 condensation may blow out therethrough. Suitable soft seats or gaskets are provided for making tight joints against the respective seats in the opposite positions of the plunger. These gaskets *l* are preferably 40 carried by the plunger itself so that they may be easily reached by withdrawing the plunger. They are held in recesses in the opposite ends of the plunger by means of nuts *m* screwing on threaded end bosses 45 on the plunger. For guiding the plunger it is formed with central longitudinal stems *p* *q* projecting from its opposite ends, the stem *p* entering a guiding recess *r* in the outlet end of the shell which incloses the 50 curved passage *d*, and the stem *q* entering a recess *s* in the cap.

For operating the plunger the usual stem G is provided, having an eccentric *t* which engages a recess in the plunger in the usual 55 way. The stem G is seated at its lower end in a step socket *v*, and its upper portion passes out through a removable packing cap H carrying a gland I of usual construction so that on unscrewing and removing the cap 60 H the stem may be lifted out through the top opening thus provided.

When the valve is arranged with its stem G vertical, as shown, this being the usual arrangement, it is common to provide an ex- 65 tension stem passing up through the car

floor and operated from within the car; the valve may, however, be turned to other positions so that the stem may be operated from beneath the car.

It is preferable, but not essential, to form 70 the seat *g* as a bushing screwed into the shell D, so that if the shell is made of iron the bushing may be of brass. It is preferable to make the plunger, or at least its stems *p* *q*, of brass or other non-rusting 75 metal.

To protect the adjusting screw *k* from injury and to lock it fast after each adjustment, so that it is guarded against working loose, a protecting nut *w* is provided 80 which serves both as a lock nut and shield. It is preferably formed as a cap nut. To adjust the screw *k* the nut *w* is removed and after the adjustment is replaced and tightened. 85

The improved train-pipe valve thus described is very convenient, compact and inexpensive, and affords advantages not heretofore realized. Since the plunger is readily accessible by lifting out the valve stem 90 and removing the cap E, the gaskets may be inspected or renewed without interfering with any of the pipe connections. The blow-off through the jet outlet *j* is readily controllable by adjustment; and if any stoppage occurs the difficulty can be easily investigated and repaired by unscrewing the cap E. There is no waste of steam blowing off through the bleeder orifices *j*, except in 95 that of the one valve at the rear end of the train; since in all of the others the plunger, by being closed against the seat *i*, shuts off these outlets. For an end valve the hose nipple may be screwed directly to the valve shell without requiring any intervening skew 100 elbow, a feature new with end valves of the plunger type. 105

The invention is not limited to the precise construction and mode of operation set forth, it being obvious that the construction 110 may be varied in details and in the arrangement of parts without departing from those features which are essential to the invention.

I claim:

1. A train-pipe valve of the type comprising a shell having a seat and a train-pipe connection, and a plunger movable in the shell to close against the seat and a plunger operating stem at right angles to the train-pipe connection, characterized in that the plunger is mounted to move out of line with the train-pipe, and the shell in addition to its connection with the train-pipe has an opening through which the plunger may be removed endwise, with a cap for closing such opening, whereby access is had to the plunger without disturbing the pipe connections. 120

2. A valve according to claim 1, wherein the shell has its plunger chamber arranged transversely to the train-pipe connection. 130

3. A valve according to claim 1, wherein the shell has its plunger chamber arranged horizontally and transversely to the train-pipe connection, and beyond the seat has an outlet for attachment to the hose curved obliquely downward.

4. A train-pipe valve comprising a shell having a seat, and a plunger movable in the shell to close against the seat, and a cap for closing the shell, with a drip outlet formed in said cap.

5. A train-pipe valve of the type comprising a shell having a seat, and a plunger movable in the shell to close against the seat, characterized in that the shell has opposite seats, the one communicating with the hose outlet and the other for closing a drip outlet, a cap for closing the shell, formed with such drip outlet, and the plunger adapted at its opposite ends to close against said seats in its opposite positions respectively.

6. A train-pipe valve according to claim 5, having the seat for the drip outlet formed on the cap.

7. A train-pipe valve according to claim 4, having an adjusting screw for varying the drip outlet.

8. A train pipe valve comprising a shell having an opening therein, and a plunger movable in the shell and removable through said opening, a cap closing said opening, said cap having a drip outlet and an adjusting screw for varying the size of the outlet.

9. A train pipe valve comprising a shell having a seat and a plunger chamber with

an opening therein, an outlet passage beyond said seat, a closed cap engaging said opening in the shell and having a second seat, a plunger movable in the shell and carrying valves coöperating with both said seats, the shell and cap having guide recesses, and guiding stems carried by the plunger and coöperating with said recesses.

10. A train pipe valve comprising a shell formed with a drip outlet, an adjusting screw for varying such outlet and extending exteriorly beyond the shell, and a closed cap engaging the protruding end of the adjusting screw and also acting as a lock nut so as to both retain and protect the screw.

11. A train pipe valve of the type comprising a shell having a seat, and a plunger movable in the shell to close against the seat, characterized in that the shell has opposite seats, one communicating with a hose outlet and the other for closing a drip outlet.

12. A train pipe valve comprising a shell having a plunger movable therein and an opening through which said plunger is removable, of a seat formed in the shell, a removable cap engaging said opening and provided with a second seat, and valves on said plunger acting alternately to engage said seats.

In witness whereof, I have hereunto signed my name.

EDWARD E. GOLD.
